(**) Term: **14 Years**

(57) **CLAIM**

(21) Appl. No.: **29/311,584**

The ornamental design for a full distribution troffer luminaire, as shown and described.

(22) Filed: **Apr. 24, 2009**

DESCRIPTION

(62) Division of application No. 29/309,543, filed on Aug. 29, 2008, now Pat. No. Des. 593,246.

FIG. 1 is an enlarged bottom left perspective view of a full distribution troffer luminaire showing our new invention;

(51) **LOC (9) Cl.** **26-03**

FIG. 2 is an enlarged bottom right perspective view of the luminaire illustrated in FIG. 1;

(52) **U.S. Cl.** **D26/76**

FIG. 3 is a top plan view of the luminaire illustrated in FIGS. 1 and 2;

(58) **Field of Classification Search** D26/72,

FIG. 4 is a rear elevational view of the luminaire illustrated in FIGS. 1-3;

D26/74-78, 118, 120-122; 362/147-150,
362/217.01, 217.05, 217.06, 217.08, 218,
362/220, 223-225, 260, 288, 307-308, 342,
362/346, 372

FIG. 5 is a left side elevational view of the luminaire illustrated in FIGS. 1-4;

See application file for complete search history.

FIG. 6 is a front elevational view of the luminaire illustrated in FIGS. 1-5;
